United States Patent Office

Des. 185,485
Patented June 16, 1959

185,485

COMBINED HELICOPTER AND AUTOMOBILE

Stefan Apostolescu, New York, N.Y.

Application October 4, 1957, Serial No. 47,984

Term of patent 3½ years

(Cl. D71—1)

Fig. 1.

Fig. 2.

Fig. 3.

Fig. 1 is a side elevational view of a combined helicopter and automobile showing my new design.

Fig. 2 is a top plan view thereof.

Fig. 3 is a front elevational view thereof.

The side of the combined helicopter and automobile not shown is a mirror image of the side shown in Fig. 1.

I claim:

The ornamental design for a combined helicopter and automobile, as shown and described.
